UNITED STATES PATENT OFFICE.

EDUARD MEISE, OF PITTSBURG, PENNSYLVANIA.

SEAL-LOCK.

SPECIFICATION forming part of Letters Patent No. 395,792, dated January 8, 1889.

Application filed September 12, 1888. Serial No. 285,217. (No model.)

To all whom it may concern:

Be it known that I, EDUARD MEISE, a resident of Pittsburgh, in the county of Allegheny and State of Pennsylvania, have invented a new and useful Improvement in Seal-Locks; and I do hereby declare the following to be a full, clear, and exact description thereof.

My invention relates to seal-locks for freight-cars, mail-boxes, express-boxes, &c., the present invention relating to certain improvements upon the seal-lock described and claimed in Letters Patent granted to me April 3, 1888, No. 380,446. The seal-lock described in said patent consists, generally stated, in a bow, which is adapted to be passed through the hasp of the lock, and a seal-plate connecting the ends of the bow, and so closing it, and a locking apparatus in one arm of the bow engaging with the seal-plate and holding it in place, the locking apparatus described in said patent consisting, generally stated, in a rotating block fitting into the end of the arm of the bow and having a cam-face formed thereon; a cylindrical pin which engages with the cam-face and the bearing for said block and permits the turning of the block in one direction, but prevents its rotation in another, this block having a locking-bar thereon which comes in contact with a stop-lug on the seal-plate. In said seal-lock, as described and shown in said patent, the seal-plate was forked at each end, one forked end passing into grooves in one arm and the other forked end engaging with the locking apparatus, and the seal-plate being held so that its face was downward, and requiring the raising of the lock to examine the seal; and where this seal-plate carried certain marks showing the place of sealing or destination of the car, as was desirable, much time was required for the inspection of the lock, it being necessary to turn up the bow to examine the sealing-plate. In the manufacture of the lock, as described in said patent, certain difficulties were also found, the principal one being that in making the body of the lock of cast metal the corrugated or roughened bearing could not well be made in the body of the bow or in the extension thereof, as shown in said patent, as this part of the apparatus required careful workmanship.

The principal objects of my invention are to overcome these objections to the use of the seal-lock by so constructing it as to always expose the face of the sealing-plate while the lock is hanging in the ordinary perpendicular position, and by providing means for securing a separate sleeve within the body of the bow; and to these ends my invention consists in improvements hereinafter particularly set forth and claimed.

To enable others skilled in the art to make and use my invention, I will describe the same more fully, referring to the accompanying drawings, in which—

Figure 1 is a face view of my improved lock, showing it sealed. Fig. 2 is a cross-section thereof on the line xx , Fig. 1, showing the sealing-plate in position for sealing and the locking-block turned in proper position to receive the plate. Fig. 3 is a vertical section of my improved lock. Figs. 4 and 5 are views of parts of the locking apparatus. Fig. 6 is a view of the sealing-plate. Fig. 7 is a view of the inspection-tag employed with the lock, and Fig. 8 is an enlarged cross-section of the locking apparatus.

Like letters of reference indicate like parts in each.

The body portion or bow a of my improved lock is preferably formed of cast-iron of proper quality, though it may also be formed of cast-steel, if so desired, it being found, however, that a body of proper strength can be obtained when it is formed of cast-iron. The body a has in one arm, b , thereof a longitudinal slot, d , for the reception of the lip of the sealing-plate, which fits into this slot d , as hereinafter described, the slot d extending in the direction of the bow, so that the seal-plate is held in the same line and its face is exposed when the body is hung in the ordinary perpendicular position, as hereinafter described.

The arm c carries the locking apparatus, which fits into the socket e cast therein, this socket e extending from one side or face of the arm c inwardly toward the other face thereof, but the wall e' , closing the base of the socket, so preventing access to the locking apparatus from this end thereof. The arm c may also have a ring, e' , by means of which the chain e^2 , connecting the body a to the car, engages with the lock.

Fitting within the socket e of the lock is the

sleeve *f*, forming the bearing of the locking-block *g*, this sleeve being preferably formed of steel and having the roughened or corrugated bearing or inner surface, *f'*, with which the 5 locking-block *g* engages. The locking-block *g* has the lock-bar *h*, the collar *i* below the bar, the cam face or faces *k*, and shoulder or shoulders *l*, and at the other end thereof the threaded stud *m*. The body portion of the 10 locking-block fits within the corrugated bearing *f'* of the sleeve *f*, the collar *i* fitting against the upper end of said sleeve and being of the same diameter, while the washer *n* screws upon the threaded stud *m* and secures the 15 block within the sleeve, the washer *n* being of the same diameter as the collar *i* and fitting against the sleeve *f*. The depth of the socket *e* in the arm *c* is equal to the length of the sleeve *f* and thickness of the collar *i* 20 and washer *n*, so that these parts fit neatly within the socket. In the sleeve *f* is formed a longitudinal key-groove, *p*, and a like groove, *p'*, is formed in the side of the socket *e*, the key *o* fitting in said grooves; and extending 25 into the sleeve *f*, nearly through the wall thereof, is a seat, *r*, which corresponds in position to a rivet-hole extending through the wall of the socket *e* and receiving a rivet, *r'*.

In order to secure the locking apparatus in 30 position in the arm *c*, the sleeve *f* is first placed over the locking-block *g* and the cylindrical pins *j* dropped into place therein, so as to engage with the cam-faces of the locking-block, and the washer *n* is then screwed on 35 the stud *m*, and so securing the said locking-block and sleeve together, and, if desired, the end of the stud *m* may be spread to hold the washer in place. The key *o*, corresponding in length to that of the sleeve *f*, is then placed 40 in the groove *p* of the sleeve, and the sleeve slipped into the socket *e* of the arm *c*, the key *o* fitting into the groove *p'* formed for it in the socket *e*, and so preventing the rotation of the sleeve within the socket, while as the 45 collar *i* extends over one-half of the key *o*, this key is held securely in place by said collar. The rivet *r'* is then driven through the arm *c* and into the seat *r*, formed in the sleeve *f*, so securing the sleeve and the 50 locking parts connected therewith from being withdrawn from the socket, and this rivet can then be filed off to prevent its being withdrawn, the locking apparatus being thus secured within the cast-metal body of the lock 55 by means of these two rivets, the rivet *r'* holding the sleeve within the socket and the key *o* preventing its rotation therein, while in so securing the sleeve within the socket the locking apparatus is also held in place thereby. 60 The seal-plate *s* is generally formed of a frangible material—cast-iron being preferably employed for the purpose—and has at one end thereof the lip *s'* and at the other end the fork *s²*, while formed at the proper place 65 thereon is the stop-lug *t*, against which the locking-bar *h* of the locking apparatus is turned. This seal-plate is secured in place

by slipping the lip *s'* into the slot *d* of the arm *b*, and then dropping the forked end *s²* over the locking-bar *h* of the locking apparatus and turning the locking-block and its locking-bar a quarter of a turn, when said bar will strike against the stop-lug, and as the cylindrical pins *j* prevent the turning back of the locking-bar and the ends of the locking-bar extend over the forked end of the seal-plate, it is evident that the seal-plate is locked in position, and that it cannot be removed, nor the bow removed from the hasp, except by breaking the plate. The seal-plate is thus 80 held with its face exposed—that is, in such position that when the bow is hanging in the hasp in the ordinary vertical position, the numbers or letters on the seal-plate can be easily read from a distance, and the necessity of turning up the lock to examine the marks on the seal-plate is overcome, this being accomplished by the improved construction of the lock, which overcomes the necessity of the locking-bar extending out from the end of the 90 bow.

As it is desirable to have means for recording the inspection to which the car is subjected in its passage from the place where it is sealed to its destination, I provide the inspection-tag *u*, which can be slipped over the arm *b* of the bow or lock-body *a* previous to the sealing of the car, the seal *s* securing this inspection-tag in place. This tag is formed of lead, leather, or other suitable material, which can either be impressed or punctured by the recording-instruments, and which is not liable to injury by exposure to the weather, and, as the car is inspected at the different points in its route from the place of its sealing 105 to its destination, the marks of the inspection may be recorded upon this tag either by impressing them into it—such as where the lead tag is employed—or by puncturing the tag—such as where leather is employed—and the 110 car can thus be regularly examined and a record of the inspections preserved by means of this tag.

When my improved seal-lock is in use, after closing the car-door and placing the 115 hinge-plate of the hasp-lock over the hasp, the free arm *b* of the lock-body *a* is slipped through the hasp and the inspection-tag *u* slipped over said arm, and the seal-plate *s* secured in place, the lip *s'* entered within seat *d* of the free arm *b*, and the fork *s²* fitting on each side of the locking-bar *h*, and the locking-bar being then turned until it strikes against the stop-lug *t*. As the locking-bar is turned, the cylindrical pins *j* of the locking apparatus are carried along by the shoulders *l*, but if it is attempted to turn the locking-bar in the opposite direction these cylindrical pins are carried back by the corrugated or roughened surface of the bearing *f'* and press 125 against the cam-face *k* of the rotating block *g*, and so prevent the turning back of the locking-bar *h*.

While the car is in transit the presence of

the seal-plate, the flat surface of which is exposed so that it can be easily seen, shows that the car has not been tampered with; but in case any person has broken the seal in order to obtain access to the car this at once becomes evident by the absence of the seal-plate.

The car sealed as above described can be carried from one to another place and properly inspected at different points while in transit, and the inspection thereof recorded on the inspection-tag, so that a proper record of the passage of the car is preserved.

What I claim as my invention, and desire to secure by Letters Patent, is—

1. In seal-locks, the combination of the bow having in one arm thereof a slot extending longitudinally of the arm, and having locking apparatus in the other arm provided with a locking-bar extending out on the side of said arm, and a seal-plate having one end fitting into said slot and the other end engaging with said locking-bar, so that the face of the seal-plate is exposed when the lock is hanging in a perpendicular position, substantially as and for the purpose set forth.
2. In seal-locks, the combination, with the bow or body *a*, having the socket *e* in one arm

thereof, of the sleeve *f*, the rotating block *g*, fitting within said sleeve, and the washer *n*, 30 holding the block within the sleeve, and means for securing the sleeve within the socket, substantially as and for the purpose set forth.

3. In seal-locks, the combination, with the body or bow *a*, having the socket *e*, provided with a keyway, *p'*, of the sleeve *f*, having the corresponding keyway *p*, the key *o*, the rotating block having the collar *i* extending over said sleeve and key, and the washer *n*, 40 engaging with said block, substantially as and for the purpose set forth.

4. In seal-locks, the combination, with a bow-shaped body and a seal-plate closing the ends of said bow and locking apparatus to 45 secure it in place, of an inspection-tag adapted to be slipped upon one arm of the body before the lock is sealed and receive any inspection-marks to be made, substantially as and for the purpose set forth.

In testimony whereof I, the said EDUARD MEISE, have hereunto set my hand.

EDUARD MEISE.
